UNITED STATES PATENT OFFICE

GILBERT ALAN ROBINSON, OF SUTTON-ON-HULL, ENGLAND

METHOD OF MAKING METAL CONTAINERS

Application filed March 31, 1932, Serial No. 602,381, and in Great Britain January 5, 1931.

This invention relates to cylindrical taper-topped cans, canisters and like metal containers of the type wherein the upper part or top of the body is of conical form, as distinguished from dome shaped, and affords a reduced outlet or neck.

It has previously been proposed to produce the domed upper portion or neck and the base of a sheet metal bottle or receptacle by forming overlapping corrugations at the end of a tubular body, and also to produce bodies of sheet-metal barrels or like vessels by a stamping or pressing operation resulting in the formation of outwardly projecting wings which are subsequently flattened against and welded or otherwise secured to the exterior surface of the vessel.

According to the invention the conical top and the wall of the body are made integral by forming from one or more blanks a tubular body which is brought to the desired shape by a series of longitudinal pleats or folds being made therein at one end, and said pleats or folds are pressed over externally or inwardly to secure the desired conical form.

In an embodiment of the invention, the sheet metal blank for the body of the can, canister or the like is rolled or otherwise formed into a cylindrical tube and the adjacent edges seamed or otherwise secured together, whereupon that end of the tubular blank which is to constitute the upper part or coned top of the body is tapered by forming therein a series of longitudinal pleats or folds appropriately spaced apart and each increasing in width toward that edge which is to constitute the outlet, the said folds or pleats being pressed or flattened over against the inner or outer face of the coned portion so formed. The reduced outlet may be fitted with the usual pouring spout or neck rim, and a handle may be secured to the tapered upper part of the can body, whilst a bottom would be secured on the opposite end of the body in the usual manner.

In order that the invention may be clearly understood and readily carried into effect, the same will now be more fully described with reference to and by the aid of the embodiment illustrated by way of example in the

accompanying perspective drawing of the upper portion of a cylindrical taper top can.

Referring to the drawing, the cylindrical can 1 is made by rolling or otherwise forming a tube of cylindrical cross-section from a blank and then forming the coned upper part 2 by folding inwardly one end of the cylindrical tube at spaced points so as to afford four double and inwardly directed triangular flaps or wings 3. This has the effect of drawing in the intermediate taper portions at the end of the cylindrical tube to attain the desired conical shape, whereupon the flaps or wings 3 are flattened against the inner faces of the conical top, as shown, and may be secured thereto by soldering or welding. A pouring spout or neck 4 is then secured in position and a bottom (not shown) is secured to the opposite end of the body to complete the can.

Although the container has been described as made from a single blank it is obvious that the invention is applicable to containers formed from two or more blanks, the blank or blanks forming the upper part of the body being treated as described.

I claim:—

The method of making a metal container from a blank which consists in forming a cylindrical body from the blank, folding the upper portion of the body at spaced points inwardly to provide a conical top and four inwardly extending triangular flaps, flattening the flaps against the inner face of the conical top, securing the flaps to the top, and inserting a spout in the reduced end opening at the mouth of the top.
